UNITED STATES PATENT OFFICE.

MOFFAT ST. CLAIR, OF GALT, ONTARIO, CANADA.

FUEL PUMP FOR COMBUSTION ENGINES.

Application filed August 7, 1922. Serial No. 580,361.

The principal objects of the invention are, to effect a very positive feed of the fuel oil to the engine in a definitely measured quantity thereby ensuring positive and uniform 5 conditions in fuel supply.

The principal feature of the invention consists in the novel arrangement of a valve within the plunger of a pump and of the means for regulating said valve whereby the 10 effective pressure stroke of the plunger is varied.

In the drawings, Figure 1 is a vertical sectional view through the pump showing the plunger in its outward position.

15 Figure 2 is a vertical sectional view showing the plunger in the inward position and illustrating the restricting action of the metering valve.

Figure 3 is a vertical sectional view 20 through the valve portion of the plunger illustrating the mechanism for regulating the metering device.

Figure 4 is a horizontal sectional view 25 through the line 4—4 of Figure 3.

28 Figure 5 is a sectional detail illustrating a modified construction of valve regulating mechanism.

In the operation of hydro-carbon engines 30 the greatest difficulty to overcome has been the regulation of the amount of fuel injected into the cylinder at each stroke. This invention has been devised to accurately regulate the amount of fuel discharged into the cylinder at each stroke of the piston and to enable such charge to be varied as may be desired.

In the construction illustrated the pump 40 is formed with a circular casing 1 which surrounds the timing shaft 2 upon which is mounted the pump operating cam 3.

The pump frame extends in an enlarged 45 open structure 6 above the cylindrical orifice 4 and in the upper end thereof is secured a cylindrical member 7 which is connected by a pipe 8 to a suitable fuel supply. The lower end of the member 7 is provided with a packing gland 9 through which the plunger rod 10 slides. The lower end of the rod is threaded into the piston guide 5.

50 A spiral compression spring 11 encircles the rod between the gland and the member 5 holding the member 5 inwardly in yielding engagement with the cam 3.

The cylindrical member 7 is seated against

a shoulder 12 and a cap 13 is threaded on 55 the upper end of the member 6 and engages the upper end of the member 7 holding it securely in place.

A cylindrical flange 14 projects inwardly 60 from the cap extending into the interior of the cylinder 7.

The cap 13 is formed with a central cylindrical chamber 15, the upper end 16 of which is reduced and threaded and in this threaded end is secured a cylindrical member 17 having a central passage 18 which forms the actual pump cylinder.

Toward the upper end of the central passage 18 is formed a tapered valve seat 19 at the bottom of a cylindrical chamber 20 and within this chamber is arranged a valve 21 ground to a sliding fit and having a tapered seat at the bottom end to engage the seat 19.

The side walls of the valve 21 are provided with longitudinal grooves 22 extending 75 from the seat to the top.

A nipple 23 is threaded in the upper end of the member 17 and is adapted to receive a pipe connection which leads to a suitable spray nozzle which sprays the oil into 80 the engine cylinder.

A coil compression spring 24 is arranged between the nipple 23 and the valve 21 and is adapted to retain the valve on its seat but which will lift under a predetermined 85 pressure.

The pump plunger is in the form of a tubular member 25 which is a sliding fit in the central passage 18 and has an enlarged lower end 26 which is threaded on to the 90 enlarged upper end of the plunger rod 10.

Within the plunger rod 10 is formed a cylindrical valve chamber 29 having a tapered seat 28 on its lower end. A valve 29 ground to a sliding fit in the chamber 29 95 and having grooves 30 in the side wall to allow the passage of oil is formed with a ground tapered seat 31 to engage the seat 28.

A fluted stem 32 extends downwardly 100 from the valve seat into a reduced cylindrical passage 33. This passage has communication with the interior of the cylinder 7 through a pair of longitudinal slots 34 through which the oil flows.

Surrounding the plunger rod 10 within 105 the cylinder 7 is a collar 35 formed with an annular groove 36 and in this collar is secured a pin 37 which extends transversely

through the slots 34 and is adapted to engage the bottom end of the stem 32 of the valve 29^a.

The position of the pin 37 in relation to the valve is regulated by an arm 38 formed with a yoke end 39 which fits into the groove 36. The arm extends laterally through a horizontally arranged hollow member 40 secured in the side of the cylinder 7 and is supported upon the spindle 41 which is journaled transversely in the member 40.

The outer end of the arm 38 is formed with a sleeve end 42 encircling the spindle 41 and is provided with a notch 43.

15 A nut 44 threaded on the spindle 41 is provided with a lug projection 45 adapted to engage the notch 43 in the sleeve end of the arm 38, thus forming a positive adjustable connection between the arm and the spindle. The outer end of the spindle is provided with an operating lever 46 which is operated to control the position of the collar 35 on its pin 37.

In the construction shown in Figure 5 the grooved collar 35 which carries the pin 37 for regulating the metering valve, is operated by a forked member 47 forming part of a sleeve 48. The sleeve 48 is slideable on a spindle 49 which is arranged parallel with the pump cylinder and is spring held by the spring 50. Within the lower threaded end of the sleeve 48 is threaded a member 51 which bears upon an eccentric 52 so that the rotation of the eccentric raises or lowers the sleeve and consequently the collar 35. The spindle 49 is formed with a squared end 53 slideable in a squared hole in the member 51 so that the rotation of the spindle adjusts the member 51 in relation to the collar 35. The spindle is provided with a knurled head 54 and a tapered seat 55 renders the spindle oil tight without packing.

In the operation of this device the oil is fed through the pipe 8 to the cylinder 7 and it completely fills the cylinder and enters the central orifice in the plunger through the slots 34.

The collar 35 is provided with holes 47 to ensure the free flow of oil to the centre of the plunger when the plunger moves upwardly through the collar and the slots are closed thereby.

As the shaft 2 is rotated, the guide 5 bearing thereon is moved upwardly or downwardly according to the position of the cam. In Figure 1 the parts are shown in position at the maximum point of discharge, that is to say, the guide 5 is resting on the apex of the cam and the top end of the plunger has reached its maximum position, the valve 21 being closed. As the cam continues to rotate the plunger moves downwardly through the action of the spiral spring 11 and the suction created by the downward movement of the plunger causes

the oil to flow upwardly through the flutes in the stem of the valve 29^a and as the plunger moves downwardly the bottom end of the stem 32 of the valve 29^a engages the pin 37 thus lifting the valve from its seat 70 and the oil flows upwardly through the grooves 30 in the head of the valve to the central passage in the plunger 25.

The cylinder of the pump, that is, the space above the tubular plunger 25 is full 75 of oil so also is the entire central passage and when the cam commences to raise the plunger, the oil will flow back through the central passage and past the valve 29^a until the plunger rises to the point where the 80 valve 29^a engages its seat 28. The back flow is then imminately checked and the further movement upward of the plunger results in the pressure of the oil being exerted to lift the upper valve 21 and force the oil 85 through the grooves 22 and on through the nipple 23 and its connecting pipe. This feature is the vital part of the invention. By the manipulating of the lever 46 or of the spindle 49, whichever construction is 90 used, the collar 35 may be adjusted to any desired position in the stroke of the pump so that the effective stroke of the pump in pushing the oil through the connecting pipes to the engine may be regulated to any desired length ranging from maximum to zero. 95

Such a regulation of fuel is found to be extremely valuable in the proper operation of an oil burning engine and the extreme simplicity of the structure ensures positive 100 operation and dependability.

What I claim as my invention is:—

1. In a fuel pump for combustion engines, a compression cylinder, a valve closing the discharge end of said compression cylinder, a plunger operating in said cylinder in sealing contact with the walls thereof and having a central passage therethrough open at the top, a valve arranged entirely within the plunger and enclosed thereby and operated by the inward flow of oil from the open top to close said central passage, passages to permit the flow of oil past the valve when it is raised from its seat, and means co-operating with said plunger valve through the side wall of said plunger to hold said plunger valve from its seat for varying the effective stroke of the plunger. 110

2. In a fuel pump for combustion engines, a cylinder, a valve closing the discharge end of said cylinder, a plunger operating in said cylinder and having a central passage therethrough open at the top, a valve arranged wholly within and enclosed by the plunger and operated by the inward flow of oil from the open top to close said central passage, longitudinal slots in the side wall of said plunger, an adjustable sleeve member encircling the valve enclosing 125 130

portion of said plunger, a pin carried by said sleeve member and adapted to enter said slots and engage said plunger valve to hold it from its seat during the initial part of 5 the stroke of said plunger.

3. In a fuel pump for internal combustion engines, a casing having a cylindrical upper portion, a removable cylindrical member disposed in the upper portion of said cylinder and having a downwardly extending portion provided with a packing nut, a cap member threaded on the outer end of said cylinder closing the upper end of said cylindrical member and engaging the same 10 to hold it in place, a compression cylinder secured to said cap, a plunger working in said compression cylinder and extending downwardly through said cylindrical member and packing nut, means for bye-passing 15 the oil from the top of said compression cylinder back through said plunger to the interior of said cylindrical member, a valve in said plunger for regulating said back- 20 flow, means for feeding fuel to the interior of said cylindrical member, and a valve closing the outer end of said compression cylinder. 25

4. In a fuel pump for internal combustion engines, a casing having a cylindrical upper portion, a cap member secured upon the outer end of said cylindrical upper portion, a cylinder supported by said cap member, a hollow plunger sliding in said cylinder and adapted to seal the cylinder walls and having an enlarged removable hollow inner 30 end, a valve arranged within the hollow portion of said plunger and adapted to close the passage therethrough, slots in said plunger below the valve, a sleeve slidable on the slotted portion of said plunger having a pin extending transversely through said slots and adapted to engage said valve 35 to hold it from its seat during a portion of the stroke of said plunger. 40
